DESIGN FOR A CLOTHESPIN

Victor H. Gillespie, Handley, and Pete E. Mokszyci, Fort Worth, Tex., assignors to Gillespie Engineering Company, Handley, Tex., a partnership

Application April 29, 1946, Serial No. 129,072

Term of patent 14 years

(Cl. D17—6)

To all whom it may concern:

Be it known that we, Victor H. Gillespie and Pete E. Mokszyci, citizens of the United States of America, residing at Handley and Fort Worth, respectively, in the county of Tarrant and State of Texas, have invented a new, original, and ornamental Design for Clothes Pin, of which the following is a specification, reference being had to the accompanying drawing, forming part thereof.

We claim:

The ornamental design for a clothes pin, substantially as shown.

VICTOR H. GILLESPIE.
PETE E. MOKSZYCKI.
